DESIGN FOR AN AUTOMOBILE-HOOD ANTENNA

Maurice S. Frankl, Brooklyn, N. Y.

Application February 7, 1938, Serial No. 74,940

Term of patent 3½ years

To all whom it may concern:

Be it known that I, Maurice S. Frankl, a citizen of the United States, residing at Brooklyn, in the county of Kings and State of New York, have invented a new, original, and ornamental Design for an Automobile-Hood Antenna, of which the following is a specification, reference being had to the accompanying drawing, forming part thereof.

The figure is a perspective view of an automobile-hood antenna, showing my new design.

I claim:

The ornamental design for an automobile-hood antenna, as shown.

MAURICE S. FRANKL.
